JOSEPH L. POTTER, OF INDIANAPOLIS, INDIANA.

DUMPING EXCAVATING-BUCKET.

1,314,700.

Specification of Letters Patent.

Patented Sept. 2, 1919.

Continuation in part of application Serial No. 846,270, filed June 20, 1914. This application filed February 9, 1918. Serial No. 216,386.

To all whom it may concern:

Be it known, that I, JOSEPH L. POTTER, a citizen of the United States, residing at Indianapolis, in the county of Marion and State of Indiana, have invented a new and useful Dumping Excavating-Bucket, of which the following is a specification, reference being had to the accompanying drawings and to the letters and figures of reference marked thereon.

This invention relates to an excavating bucket of the type that is designed to operate as a scoop or drag bucket in connection with various means for hoisting and carrying the bucket, the invention having reference more particularly to means for directly lifting and carrying the bucket and permitting it to be manipulated so as to quickly discharge its load; the invention having reference also to improved means for operating and controlling the bucket in operation. The invention relates also further to the apparatus disclosed in my prior application for Letters Patent filed June 20, 1914, Serial No. 846,270, the present application being a continuation of said prior application in so far as the subject matter is common to both applications.

An object of the invention is to provide an improved dumping excavating bucket that shall be so constructed as to be capable of being conveniently and quickly operated and controlled, and which shall be simple and inexpensive.

Another object of the invention is to provide improved means whereby to operate and control dumping excavating buckets by means of various types of apparatus, and especially apparatus whereby to hoist and carry the bucket.

A further object is to provide an improved excavating bucket which shall be so constructed as to be free from various movable parts, such as drop bottoms or doors, latching devices, etc., which are liable to become damaged or deranged in operation and cause trouble and expense for repairs.

A still further object is to provide simple means whereby excavating operations may be economically carried out by the minimum number of operators or attendants, which means shall be so constructed as to be reliable and durable in use.

With the above-mentioned and other objects in view, the invention consists in an

improved dumping excavating bucket and controlling appliances therefor whereby the bucket may be operated as a scoop and lifted so as to elevate its load, and whereby the bucket may be shifted relatively to its support and permitted to tilt or turn over and discharge its load. The invention consists also further in the novel parts and combinations and arrangements of parts as herein-after particularly described and further 65 pointed out in the appended claims.

Referring to the drawing, Figure 1 is an elevation partially broken away showing the apparatus comprised in the invention in working arrangement in a trench; Fig. 2 is 70 a side elevation of the improved apparatus with the bucket in dumping position, the bucket being shown in section longitudinally; Fig. 3 is a side elevation of the improved bucket slightly modified as to 75 details, being of the specific form disclosed in said prior application for Letters Patent; and, Fig. 4 is a side elevation of the improved bucket and apparatus showing the bucket in position for excavating, the bucket 80 being in section longitudinally.

In the different figures of the drawing similar reference characters indicate like elements or features of construction herein referred to in detail.

A practical embodiment of the invention includes a suitable bucket body which preferably comprises a bottom 1 of suitable construction and form, a back or rear end 2, a top portion 3 connected with the back, side 85 members 4 and 5 connected to the bottom and the back and also to the top portion and having forwardly-extending upper portions, and the transverse member 6 connected with the tops of the forward portions of the side 90 members. For the purposes of the present invention the member 6 of the bucket body preferably is provided with longitudinally centrally arranged ribs 7 which support a sheave 8 at the forward portion thereof, the 95 ribs having apertures 9 rearward of the sheave. A separate unyielding slide bar or balancing bar 10 is secured to the top portion 3 and also to the transverse member 6 of the bucket body so as to extend longitudinally thereof midway of the side members of the body, and it has a suitable number of apertures 11 therein to receive bolts or pins. A yoke 12 is slidably arranged on the bar 10 and provided with a securing bolt 13 110

which may be placed in either one of the apertures 11 or may be removed to permit the yoke to slide on the bar to be stopped either against the member 6 or against a 5 stop bolt 14 which is removably inserted in one of the apertures of the bar.

- The bucket or scoop body is provided with a suitable handle or handling devices which may be variously constructed and arranged 10 as to details and has connection with the rear portion of the bucket body. Preferably the body is provided with an ear 15 or ears at the rear end of the bottom 1, and in some cases the back or rear end 2 has a rib 16 15 on its outer side. Preferably the handle or handling devices comprise a suitable cable 17 so that the bucket shall have a flexible support, the cable being connected either to the ear 15 as shown in Fig. 4 or to the rib 16 as 20 shown in Figs. 1 and 2, the cable extending upward over the bucket body and forwardly and being provided with a suitable clevis or coupler 18 to permit shifting of its connection with the bucket body, and by which 25 it is connected either with the yoke 12 as shown in Fig. 4 or with ribs 7 as shown in Figs. 1 and 2. The handling device extends over and is supported upon a roller 19 which is mounted in a suitable carriage 20 which 30 may be variously constructed and movably supported, the carriage preferably being provided with a sheave 21 at a suitable distance forward of the roller, and in some cases is provided with two wheels 22 and 23 35 which are supported to roll on a slack-line or aerial cable 24 which is suitably supported and extends over a supporting sheave 25 to be controlled as in common practice by means of a winding drum, the cable being 40 provided with a stop-block 26 whereby to stop the carriage at the desired position for dumping operations. In some cases the carriage 20 is provided with a single centrally arranged wheel or sheave 27 to be supported 45 on a cable 28 which may be variously raised or lowered, as by means of a crane boom.
- The forward portion of the bucket body is provided with a draft line or cable 29 which has links or bridle portions 30 and 31 50 directly connected with the extensions of the side members of the bucket body and has also a branch 32 that extends over the sheave 21 whereby the branch is guided and supported, the branch 32 extending under the sheave 8 55 and thence to the cable or handling device 17 and is connected thereto at a suitable distance from the end that has the connecting device 18. The line or cable 29 may be variously operated for dragging the bucket, 60 as will be understood, and in some cases the branch 32 is provided with a hook or connecting device 33 which is detachably connected with the line or cable 29, as by means of a link 34 connected thereto.
- 65 In some cases the bucket body is slightly

modified and comprises a suitable bottom 1', a back or end 2', and side members 4'. The upper forward portion of the body has a transverse member 6'. The body is provided with a suitable handle or handling device adapted to ride on a roller or pulley and to be stopped at either one of the different points to tiltingly support the bucket body, to balance the body or to over-balance it, as may be desired. In the present case the handling device is composed of a stiff metallic bar which is suitably bent and has connecting members 35 and 36 secured to the member 6' and the back 2' respectively, the device having a crook 37 which is located in proximity to the forward portion of the bucket body, the device having also a crook 38 adjacent to the rear end of the body, the crooks being adapted to be supported on the roller or sheave 19, and the handling device has an eye or lug device 39 connected thereto forward of the crook 37 whereby to draw the crook forward from the roller so that the main portion 40 of the device shall ride upon the roller. The bucket is to be dragged by the line or cable 29 and its bridle portions, the line or cable having a branch 32' that is connected with the eye 39. The roller or sheave 19 is carried, as above stated, by a suitable carriage 20'. When the main portion 40, which is straight, is resting upon the roller 19 the bucket body may be suspended in balanced arrangement.

In the practical operation of the excavating bucket the cable for supporting it is permitted to be slackened so as to lower the bucket to the desired place, the bucket in its descent drawing out the cable or line 29; and when the bucket is on the ground the carriage may be permitted to descend on to the top of the bucket to add weight to the bucket and thus assist in holding the bucket down during the digging movement. Power being applied to draw the cable 29, it is evident that the bucket is thereby drawn forward so as to scoop in a load of sand or earthy substance, in some cases the bucket being drawn forward relatively to the supporting carriage so as to bring the bucket body mainly under the carriage. Upon drawing up the carriage for hoisting the load the cable 29 may be manipulated so as to enable the branch 32 to draw up the forward end of the bucket body, by means of the sheaves 8 and 21, further tightening of the branch 32 115 causing the forward portion of the cable 17 to be flexed forwardly, as shown in Fig. 4, while the forward end of the bucket may be further elevated so as to be in position somewhat as represented in Fig. 3 to retain 120 its load. In case the bucket body is provided with the rigid handle, when the carriage is elevated the roller 19 follows the inclined under side of the bar 40 to the crook or crotch 37, after which the bucket is carried 125 130

upward by the roller. When the carriage is drawn forward and stopped the cable 29 is caused to continue forward movement so as to draw the branch 32, or the branch is independently drawn forward, if necessary to over-balance the bucket body forwardly, after which the cable or line 29 is slackened to permit the bucket to turn over forwardly and discharge its load, which position is seen in Fig. 2. In the case of the bucket having the rigid handle the branch 32' draws the handle forward over the roller 19 until the crook 38 is brought on to the roller so as to support the bucket as it tilts forward and discharges its load. In either case the bucket is caused to turn over forwardly with promptness so as to quickly discharge its load. The bucket is returned to the excavation and the operations repeated as may be required.

When the bucket is required to handle sticky mud or soil which may adhere to the bucket in attempting to discharge the load, it will be an advantage to permit the yoke 12 to freely slide along the bar 10, and permit the cable 32 to draw the yoke forward to the member 6 when filling the bucket, so that when the bucket is turned to an inclined angle to begin discharging its load the bar 10 will slip through the yoke and let the bucket rapidly descend until the rear portion 3 of the bucket engages the yoke and causes the bucket to abruptly stop in its descent, which jars the load loose from the bucket and insures ready discharge of the load. A similar result is obtained in the use of the bar 40 when the stop portion 38, suddenly stopped on the roller 19, causes a jar which dislodges the load.

Having thus described the invention, what is claimed as new is—

1. An excavating bucket including a bucket body with a sheave on its forward portion, a straight handling bar secured to the forward and rearward portion of the body, a handling cable connected with the rearward portion of the body and also connected with the handling bar to permit slip of the bar relatively to the cable connection, and a controlling cable extending under the sheave and connected to the handling cable adjacent to its connection with the bar.

2. An excavating bucket comprising a bottom and a back end and sides connected thereto, the upper portions of the sides extending forward beyond the lower portions thereof and having a transverse member

thereon, a longitudinal rib rigid on the transverse member and having apertures therein, a handling cable connected with said back end and in one of said apertures with the rib, and means for slidably connecting the cable with the transverse member when disconnected from the rib.

3. In excavating apparatus, the combination with a roller provided with a carriage device for carrying the roller, and a scoop body, of a sheave mounted on the forward portion of the scoop body, a balancing bar secured to said body, a handling cable connected with the rearward portion of said body and extending over said roller, means for connecting the cable either to the forward portion of said body or to said bar, and a controlling cable guided by the carriage device and extending under said sheave to and connected with the handling cable.

4. In excavating apparatus, the combination of a carriage, a wheel to support the carriage, a sheave and a roller spaced a long distance apart in the carriage, a drag bucket body having a transverse forward top member on its sides, a straight balancing bar secured rigidly to said member and also to the rear portion of the bucket body, a guide device mounted on said member, a handling cable connected with the rear portion of the bucket body and also with said bar and extending over said roller, and a controlling cable connected to said handling cable between said roller and said bar and extending directly to and under said guide device and thence to and over said sheave.

5. In excavating apparatus, a drag bucket comprising a bottom and sides and also a back end, a transverse member secured to said sides, a straight balancing bar having one end rigidly secured to the under side of said member and its opposite end rigidly connected with said back end, a pair of ribs rigidly secured on the upper side of said member and having apertures therein, a yoke slidably arranged on said bar, and a handling cable connected with the back end of said bucket and having a shackle to be connected with either the yoke or the apertures in said ribs.

In testimony whereof, I affix my signature in presence of two witnesses.

JOSEPH L. POTTER.
